UNITED STATES PATENT OFFICE.

CHRISTOPHER GALLACHER, OF JASPER, ALABAMA, ASSIGNOR TO GOODMAN MANUFACTURING COMPANY, OF CHICAGO, ILLINOIS, A CORPORATION OF ILLINOIS.

MINING APPARATUS.

1,411,341.

Specification of Letters Patent.

Patented Apr. 4, 1922.

Application filed May 18, 1920. Serial No. 382,497.

To all whom it may concern:

Be it known that I, CHRISTOPHER GALLACHER, a citizen of the United States, residing at Jasper, in the county of Walker and State of Alabama, have invented an Improvement in Mining Apparatus, of which the following is a specification.

This invention relates to improvements in apparatus for handling loose material, and more particularly to scraping devices for transporting coal from the working face of the mine to the entry for loading in mine cars. The object of the present invention is to provide a more efficient apparatus of the class described.

My invention may best be understood by reference to the accompanying drawings, in which Figure 1 is a view of the scraper or scoop embodying my invention.

Figures 2 and 3 are diagrammatic views of a mine room and scraper loading system, illustrating the use of my invention.

Figures 4, 5 and 6 are detailed views of the tail rope hook.

Fig. 7 is a view of a modified form of the tail rope hook.

My invention is particularly adaptable to assist in the so-called "scraper loader" system of coal handling, of which a typical apparatus is illustrated in Figures 2 and 3. A scraper 1 is provided with a head rope 2 and tail rope 3, each of said ropes being operated by a suitable hoisting engine of the usual type (not shown), usually situated outside of the mine room, in the entry or gallery 4. The head rope 2 is adapted to be led over a detachable sheave 5 anchored in one corner of the room adjacent the working face 6. The tail rope 3 is led around the stationary sheave 7 anchored in the opposite corner of the room, and from thence around suitable guiding sheaves to the hoisting engine. In starting the loading operation, the scraper is dragged by the tail rope 3 to the far corner of the room adjacent the stationary pulley 7. The tail rope 3 is then allowed to run free, and the head rope 2 is led around the detachable sheave 5. With this arrangement, when the head rope is pulled by the hoisting engine, the scraper moves along the working face 6 of the mine wall, to collect the loose material adjacent thereto, and thence turned toward the entry by detaching the head rope 2 successively from the sheave 5, and a second

detachable sheave 8. The head rope 2 is then disengaged from the sheave 8, and the straight pull is exerted on the scraper to move it outwardly to the entry where it is loaded into cars in the usual manner. 60

A deflector or guide pulley 9 is usually placed in a position near, but spaced from the detachable sheave 5 in order to maintain the scraper in a path along the side of the room in its movement to and from the entry, as a large portion of the room is usually occupied with waste material or mine props around which the scraper must move. When the head rope 2 is detached from the sheave and the scraper moves toward the entry, the tail rope 3 engages the deflector or buffer guide 9. 70

A preferred construction of scraper used with systems such as described is illustrated in Figure 1, which comprises a bottomless 75 body portion 10 having substantially upright side walls 11, 11 converging at the rear of the scraper in a rounded rear end portion 12.

One difficulty has been met with in manipulating the scraper to load the coal in the far corner of the room adjacent the sheave 7, when the scraper is in starting position. The scraper is necessarily of considerable weight, and must be shifted laterally to several positions in order to gather the loose coal in this corner. Another difficulty has been in scraping close to the working face 6, which heretofore has been accomplished by directing the scoop toward 90 the face before the pull is exerted on the head rope.

In the present invention, I provide the scraper 1 with a permanent tail rope connection 13 on one side of the scraper, and 95 with a detachable connection 14 for the tail rope substantially on the longitudinal center line of the scraper. In other words, the rope is permanently attached to the side of the scraper nearest the working face of 100 the mine, and is adapted to be engaged or disengaged at the rear end 12 of the scraper. The permanent connection for the tail rope may be of any construction, as for instance an eye 15 attached to the side of the scraper, 105 at a point which will cause the scraper to be drawn rearwardly at an angle to its normal line of forward movement. A preferred construction of the detachable connection comprises an inverted hook 16, 110

opening forwardly and downwardly so as to retain the tail rope in engagement therein while the pull on the tail rope is substantially in a rearward direction, but in which 5 the rope may become automatically disengaged when the scraper reaches the deflector, and the pull of the rope changes to an angular direction with respect to the longitudinal center line of the scraper, as shown 10 in dotted lines in Figure 1. With this device, the tail rope may be slipped into the hook 16 by the operator at any time during the forward movement of the scraper.

Another form of hook is shown in Figure 15 7, in which the tension of a spring 17 is sufficient to retain the rope in place until disengaged by the operator, or by the change in direction of pull of the tail rope, as above described.

20 With an improved arrangement of tail rope connections as above described, it will be seen that the tail rope 3 may be disengaged from its rear end connection 14, so that the scraper 1 approaches its starting 25 position at an angle to the face, as shown in Figure 2. In this position, the scraper can gather a larger proportion of coal immediately adjacent the sheave 7, thereby minimizing the lateral shifting of the scoop, or 30 the shoveling ordinarily necessary in order to gather all the loose coal in this corner. This feature is particularly advantageous in gathering coal under a low roof where difficulties of handling the scoop or shoveling are 35 increased by the limited head-room. Furthermore, it will be noted that the scoop may be drawn rearwardly to a position in 40 which it is directed toward the face. In gathering systems of this kind, the scraper usually makes several trips in one setting of the apparatus. The operator may pull the scoop rearwardly either in an angular or straight position to any place desired along the mine face.

45 Although I have described a specific loading system with which my invention is particularly adaptable, it will be understood

that my invention may be applied to other loading systems, as for instance, in which the movement of the scraper may be in one 50 direction without turning, but in which it is equally necessary to direct the scraper toward the mine wall in its initial movement. Furthermore, it will be understood that many variations may be made in the 55 specific construction and arrangement of the tail rope connections without departing from the spirit and scope of my invention.

Having described my invention what I claim as new and desire to cover by Letters 60 Patent, is:

1. In a scraping apparatus, a scraper provided with a head rope adapted to move the scraper in a forward direction to load the same, and a tail rope connection with said 65 scraper, and adapted to move the scraper in a rearward direction, either on the normal line of forward movement of the scraper and head rope, or turned on a vertical axis at an angle to its normal position, at will. 70

2. In a scraping apparatus, a scraper provided with a head rope adapted to move the scraper in a forward direction to load the same, and a tail rope adapted to have connection at will to the rear end of said scraper 75 or at one side thereof.

3. In a scraping apparatus, a scraper provided with a head rope adapted to move the scraper in a forward direction to load the same, and a tail rope having permanent connection with said scraper at one side thereof, and a detachable connection at the rear end 80 thereof.

4. In a scraping apparatus, a scraper provided with a head rope adapted to move the 85 scraper in a forward direction to load the same, a tail rope having permanent connection with said scraper at one side thereof, and a detachable connection at the rear end thereof, and means responsive to the direction 90 of pull on said detachable connection for disengaging said tail rope therefrom.

CHRIS GALLACHER.
